His Attorney.

UNITED STATES PATENT OFFICE

2,249,499

ELECTRIC CIRCUIT INTERRUPTER

Joseph W. Seaman, Upper Darby, Pa., assignor
to General Electric Company, a corporation of
New York

Application December 2, 1938, Serial No. 243,587

5 Claims. (Cl. 200—144)

My invention relates to electric circuit interrupters, more particularly to air circuit interrupters of the type wherein the arc is to be interrupted within confining or partially confining means, such as an arc chute, and has for its principal object the provision in an air circuit interrupter of the character above defined of improved arc-interrupting means that is effective rapidly to extinguish a high voltage power arc within a comparatively small space, and to confine under all operating conditions the arc within this space.

The use in arc chutes of arc cooling and quenching structures, such as metal or insulating plates, between which the arc is driven, and spaced metal pins or bars positioned transversely of the arc path is known in the air circuit breaker art. In a well-known form, a circuit breaker of the magnetic blow-out type is provided with a plurality of spaced metal plates within an arc chute arranged so that the arc, as it is driven into the plates by the blow-out field, is divided into a plurality of serially related sections.

It has also been proposed to use in the arc chute spaced metal pins or bars for the purpose of cooling and quenching the arc. The design factors, however, have not been clearly understood, particularly with respect to the spacing and arrangement of the arc-quenching elements, with the result that arc interruption has not been reasonably consistent except in the case of spacious arc chutes having a large aggregate mass of cooling material.

I have found that in the case of spaced metal elements, such as pins or bars, there is an optimum for the relative spacing of these elements within the arc chute, regardless of both the aggregate mass of cooling metal within the chute and the magnitude of the current to be interrupted. This optimum spacing results in a compact and efficient arc chute for a given interrupting rating. Specifically, I have found that pins composed of a suitable non-magnetic metal, such as copper for example, positioned transversely of the arc path between the insulating walls of an arc chute are most effective for arc interruption when spaced approximately $\frac{1}{8}$ " from each other, the spacing being between adjacent pin arcing surfaces as contrasted with pin centers. A tolerance of plus or minus $\frac{1}{16}$ " is within the scope of my invention, although the $\frac{1}{8}$ " spacing is preferred.

I have also found that an arc chute provided with arc-extinguishing structure of the character

above described can also be made even more effective and compact by the use of an insulating arc baffle structure at the exhaust end of the chute. The baffle structure is made up of baffle plates spaced so as to form a plurality of approximately parallel narrow slots each approximately $\frac{1}{8}$ " in width extending substantially parallel to the arc path. These slots are effective not only as an aid in extinguishing the arc in case it is driven through the main arc extinguishing means, but also to prevent extension of the arc exteriorly of the chute. The slots however provide free venting of the arc gases within the chute.

15 My invention will be more fully set forth in the following description referring to the accompanying drawing, and the features of novelty which characterize my invention will be pointed out with particularity in the claims annexed to and forming a part of this specification.

15 Referring to the drawing, Fig. 1 is an elevational view, partly in section, of the essential portion of an air circuit breaker embodying the present invention; Fig. 2 is an end view of the 20 circuit breaker structure shown by Fig. 1, and Fig. 3 is an enlarged detail view of the arc interrupting structure.

The electric circuit interrupter shown by Figs. 1 and 2 comprises an air circuit breaker having 25 separable contacts 1 and 2, between which the arc is formed upon opening of the main power circuit and an arc interrupting structure generally indicated at 3 for receiving and extinguishing the arc. The circuit breaker is mounted on 30 an insulating support or panel 4 through which a terminal conductor 5 connected to the fixed contact 1 extends. The movable contact 2 is carried on a operating arm 6 that is secured to 35 an insulating shaft 7 for rotative movement 40 therein and has a resilient connection at 6' with the main operating arm for permitting limited overtravel or "wipe" when the contacts are closed.

The arc-extinguishing structure or arc chute 3 45 comprises in the present instance a pair of spaced insulating plates 8 composed of asbestos board or the like forming an arc chamber that is adapted at its lower end to receive the arc and to vent the arc gases at the upper or exhaust end. The arc chute is substantially closed at 50 one side by the arcing horn 1' and an insulating spacing and supporting member 9 secured to the support or panel 4, and at the opposite side by the arcing horn 2'. As illustrated, the arcing horn 1' forms part of the fixed contact structure 55 and is secured in position by the terminal con-

ductor 5. The arcing horn 2' is secured between the insulating plates 8 by an insulating spacing member 10. The arc chute so far described is of a more or less conventional design, the arc formed between the contacts 1 and 2 being blown by a magnetic field, for example, into the arc chute along the arcing horns 1' and 2' so that the arc is greatly lengthened and cooled.

For the purpose of greatly increasing the interrupting capacity and efficiency of the arc chute, a compactly arranged group of spaced metal elements, such as copper pins 11, are mounted between the plates 8 so that the pins extend preferably in staggered rows as shown transversely of the arc. As previously stated, the copper pins are preferably spaced from each other approximately $\frac{1}{8}$ " with respect to the adjacent arcing surfaces of the pins. That is, the outer cylindrical surfaces of the pins are spaced approximately $\frac{1}{8}$ " from each other throughout the arc chute. The theoretical reasons for this precise spacing are not believed necessary for a clear understanding of the invention as it has been definitely proved that improved interrupting action takes place when the pins are so spaced. It is of particular importance to note that this spacing is substantially independent of the magnitude of the current to be interrupted and also of the exact number of pins within the chute, assuming, of course that there is sufficient mass of metal within the chute to dissipate the initial heat of the arc so that the pins are not vaporized greatly. The spacing is also substantially independent of the voltage impressed across the circuit breaker terminals, although it should be understood that for high voltages an increase in size of the arc chute structure is necessary.

Under normal interrupting conditions the arc enters the chute along the arcing horns 1' and 2' and is split up as it moves among the pins so that extinction generally occurs well within the chute. In the case of heavy overloads or short circuits, the arc may be driven toward the exhaust or upper end of the chute. In such cases I have found that spaced parallel insulating baffles 12 arranged to form a plurality of narrow slots are effective to maintain the arc within the chute and also to cause final extinction. The narrow slots, although very effective to prevent extension of the arc exteriorly of the arc chute, provide sufficient exhaust area openings to permit free venting of the arc gases formed within the chute.

As shown, the insulating baffles 12 comprise a plurality of arcuate strips of suitable arc resisting insulating material, such as asbestos board or the like clamped between the upper edges of the plates 8 by means of through bolts 13 and insulating spacers 14. The baffles preferably extend throughout the length of the exhaust end of the chute. The slots so formed are preferably $\frac{1}{8}$ " in width or less as I have found that a number of narrow slots having a sufficiently large aggregate exhaust gas venting area are most effective in maintaining the arc within the chute and aiding arc extinction. If desired, an integral moulded baffle structure can be used.

An air circuit breaker constructed as above described is compact in size as compared with air circuit breakers of similar rating having the conventional type of arc chutes. Furthermore, arc interruption is more consistent and the duration of arcing is considerably less.

The arc can be driven into the arc chute by 75

conventional magnetic blow-out means, although in the present instance I have shown a magnetic structure associated with each of the contacts for initiating movement of the arc along 5 the arcing horns into the chute. This magnetic structure comprises a pair of yokes 15 and 16 composed of iron or other suitable magnetic material. The yokes are secured, as illustrated, to the contacts so that the open ends face each 10 other in a position offset with respect to the point of contact engagement so as to be more remote from the arcing horns. That is, the iron yokes are mounted somewhat beneath the point of engagement between contacts 1 and 2 so that there 15 will be present upon separation of the contacts a magnetic flux tending to drive the arc into the arc chute. The arcing horn 2' and the movable contact 2 are connected as in the usual case through flexible conductors 13 to the other terminal of the circuit breaker (not shown).

It has been found that in severe arc interrupting duty, the copper pins 11 are burned or fused considerably at or adjacent to the side walls of the chute. I have found that this can 20 be substantially prevented by spacing the pins from the supporting insulation that is in flush alignment with the inner sides of the arc chute. Specifically, this can be done by forming enlarged recesses in the insulating side walls for receiving 25 the copper pins as illustrated by Fig. 3. With this arrangement the ends of the pins seat within cylindrical recesses at 18, each cylindrical recess being countersunk as at 19 to form a conical recess so that the pins are spaced from that 30 part of the wall insulation that is flush with the inner sides of the chute. This arrangement serves effectively to prevent excess fusing of the pin metal at the side walls of the chute. An alternate arrangement consists in turning down 35 the ends of each pin a certain distance so as to increase the spacing between the pins where they are in contact with the side walls of the arc chute.

It should be understood that my invention is 40 not limited to specific details of construction and arrangement thereof herein illustrated, and that changes and modifications may occur to one skilled in the art without departing from the spirit of my invention.

50 What I claim as new and desire to secure by Letters Patent of the United States is:

1. An electric circuit interrupter having arc-forming means and an arc chute for receiving the arc comprising spaced insulating side walls and a compactly arranged group of metal pins mounted between said insulating walls transversely of the arc, the adjacent arcing surfaces of said pins throughout said chute being spaced substantially uniformly from each other approximately $\frac{1}{8}$ ".

2. An electric air circuit interrupter having arc-forming means and an arc chute for receiving the arc comprising spaced insulating walls open at one end for venting the arc gases, a compact group of metal pins mounted within said chute between said walls in substantially uniformly spaced relation to extend transversely of the arc path, the spacing of said pins from each other at the arcing surfaces thereof being approximately $\frac{1}{8}$ ", and insulating baffle structure disposed beyond said pins at the exhaust end of said chute, said baffle structure forming a plurality of narrow slots not exceeding $\frac{1}{8}$ " in width parallel to the arc for confining said arc within said chute.

3. In an electric air circuit interrupter having arc-forming means, an arc chute comprising a pair of spaced insulating walls and a plurality of metal pins mounted in said plates so as to extend between said walls, the ends of said pins being mounted within conical shape recesses in said insulating walls for minimizing fusing of the pin metal at said walls.

4. In an electric air circuit interrupter having arc-forming means, an arc chute comprising a pair of spaced insulating walls and a plurality of metal pins mounted in said plates so as to extend between said walls, the ends of said pins being mounted within enlarged recesses in said

insulating walls whereby the insulation of said walls in flush alinement with the inner sides of said chute is spaced from said pins.

5. In an electric air circuit breaker having arc-forming means, an arc chute comprising a pair of spaced insulating walls and a plurality of metal pins mounted in said plates so as to extend between said walls, the metal adjacent to the ends of said pins subject to arcing being spaced with respect to the insulation surfaces of said walls for minimizing fusing of the pin metal at said walls.

JOSEPH W. SEAMAN.
